UNITED STATES PATENT OFFICE.

JOHN A. SHEPHARD, OF NEW YORK, N. Y.

DESIGN FOR A BOTTLE, &c.

SPECIFICATION forming part of Design No. 23,413, dated July 3, 1894.

Application filed May 5, 1894. Serial No. 510,224. Term of patent 14 years.

To all whom it may concern:

Be it known that I, JOHN A. SHEPHARD, a citizen of the United States, residing at New York city, in the county of New York and State of New York, have invented and produced a new and original Design for Bottles and Vases; and I do hereby declare the following to be a full, clear, and exact description of the invention, such as will enable others skilled in the art to which it appertains to make and use the same, reference being had to the accompanying drawing, and to the letters of reference marked thereon, which forms a part of this specification.

15 The design is illustrated in the accompanying drawing which is an exterior view in elevation.

20 My design is applicable to bottles, and other similar receptacles, and I have shown it in the accompanying drawing as applied to a decanter.

25 The material of which the article is composed to which my design is applied is not essential, as it may be of glass, clay, metal or any other suitable material.

Referring to the drawing, the design consists of three principal parts, the base, A, the body, B, and the neck, C.

The design as a whole resembles a thistle, which is its characteristic feature the drawing in this case showing the thistle reversed, that is the base A is the corona or flower, the part, B, the body or calyx, and the part C the stem. The part A is conoidal in form, or somewhat bell shaped, flaring downward from the body B as shown, and is provided with a series of flutes, *a*, on its surface. The body B is circular in form and is provided with diamond shaped protuberances, *d*, to represent the prickly leaved portion of a thistle. 35 The neck C is somewhat conoidal in form and in the position shown flares downward from the mouth of the bottle to the body, and is provided on its surface with flutes, *e*, and at its top with a flange, *g*.

40 What I claim is—

45 The design for a bottle or similar receptacle herein shown and described.

In testimony whereof I affix my signature in presence of two witnesses.

JOHN A. SHEPHARD.
